R. G. Babcock,

Horseshoe Machine,

No 8,067.

Patented Apr. 29, 1851.

Fig. 1.

Fig. 2.

UNITED STATES PATENT OFFICE.

ROBERT G. BABCOCK, OF NEW LONDON, CONNECTICUT.

HORSESHOE MACHINE.

Specification of Letters Patent No. 8,067, dated April 29, 1851; Antedated February 24, 1851.

To all whom it may concern:

Be it known that I, ROBERT G. BABCOCK, of New London, in the county of New London and State of Connecticut, have invented 5 a new and Improved Machine for Bending, Drawing, and Chamfering Horseshoes; and I do hereby declare the following to be a full, clear, and exact description of the same, reference being had to the accompanying drawings, making a part thereof, in which—

Figure 1, represents a top view, with the top plate removed. Fig. 2, represents a longitudinal vertical section through the machine.

Similar letters in the several figures represent the same parts.

The nature of my invention consists in bending, drawing and chamfering horse shoes at the same operation, the machine being so adjustable as to be adapted for making larger or smaller shoes, and the draft of the shoe from toe to heel be drawn out by a pattern to any form desired.

25 To enable others skilled in the art to make and use my invention, I will proceed to describe the same with reference to the drawings.

On one end of a substantial wooden frame 30 A, firmly bolted to a stone foundation, are placed the boxes B B, resting and turning in which, on its journals, is the shaft C. Upon said shaft C, is placed the pulley D, over which the band that drives the machine 35 may pass, and on the end of said shaft outside of the frame is placed the balance wheel E; on said shaft is also placed the spur wheel F, which meshes into a cog wheel G, which is placed on a shaft H, which has its 40 bearings in the pillar blocks I, said pillar blocks being firmly secured to the frame aforesaid. Upon the end of the shaft H, is placed the crank J, which plays between the longitudinal timbers of the frame. To a 45 wrist on said crank J, is attached a connecting rod K, the other end of which said connecting rod is attached to a cross head L, to be hereafter described. On the other end of the frame is arranged the bed plate M, on 50 which the machinery is erected. On said bed plate, are cast the ways a, a, which have angular projection thereon on their inside, which fit into corresponding angular

grooves on the ends of the cross head L, and by which the cross head is guided in its motion. On the top of said cross head, are cast the lugs b, b, which have holes through them for the key bolt c, to pass through, and which key bolt also passes through holes in the arms N, N, allowing said arms to rise 55 up and swing back, when it becomes necessary to adjust the parts below said arms for making larger or smaller shoes. The arms N, N, are enlarged both above and below at their outer extremity, for the purpose of 60 forming supports for the shaft d, of the drawing roller O, in the lower projection, and the shafts e, of the guide rollers P, P, in their upper projection.

Supported on the uprights Q, which are 70 firmly secured to the bed plate, is a plate or cap piece R, which is made adjustable by means of the screw nuts f, both above and below said cap piece, which said nuts fit onto screws cut on the upper ends of the 75 aforesaid uprights Q. Sliding in grooves made in flanges on the underside of said cap piece R, are wedge shaped pieces or patterns g, for drawing the horse shoe by, and giving them the proper taper from toe to 80 heel. The guide rollers P, P, as the cross head advances, run upon the wedge-shaped pieces or patterns g, and guide the drawing roller O, allowing said drawing roller to rise or fall as it advances upon the horse 85 shoe, and giving said shoe the desired draft from toe to heel. By substituting for the drawing roller herein described, other proper shaped rollers, and for the wedge shaped pattern, other suitable patterns, I 90 am enabled to draw out ax-skelps, block hooks, and many other irregular forms, and for which purpose, I intend also to apply my machine.

Instead of the guide rollers arranged as 95 herein described, they may be made larger, and placed on the same shaft with the drawing roller, and run in grooves or guide pieces in the bed plate, and in which latter position I may use them if found essential.

In a socket S, cast on the opposite end of the cross head from where the connecting rod is attached to it, is inserted the tang h, of a fork-shaped piece T, said piece being made adjustable in the socket of the cross 105 head, by means of a set screw i, and when

run out so that the shoulder on said fork-shaped piece T, does not rest against the shoulder of the socket, a washer may be placed on the tang, so as to give it sufficient strength to accomplish its intended object.

5 The jaws k, of the fork-shaped piece T extend forward of the drawing roller O, and on the underside, in the extreme ends of the inside of said jaws k, are placed the pins 10 l, l for catching the blank on each side of the former U, and bending said blank into proper shape around said former. The heel of the fork-shaped piece T, is rounded so as to make it in form like a staple, and 15 slightly flaring, so that by setting it back or forward in the socket on the pillar block a larger or smaller shoe may be formed over the same former. On the underside of said heel is cut a recess m, which is so inclined 20 as to give the proper chamfer to the shoe after it is drawn out by the roller O, the shoe being drawn out thinner at the toe than at the heel.

In the bed plate is fixed a mold of steel n, 25 which rests upon a plate o, extending across the longitudinal pieces of the frame under the bed plate. In a suitable hole in this mold is placed the former U, which stands up sufficiently high above the bed plate to 30 catch the blank, as it is forced up against said former by the pins l l, the lower end of said former resting upon a spring p, which as the drawing roller O, comes upon said former, allows it to sink, leaving the 35 whole pressure of the drawing roller upon the shoe, and after the roller has passed, the spring p, immediately raises the former in proper position for the next operation. To prevent the former from being clogged 40 by the cinder from the iron, I sometimes place a light trip hammer below it, worked by cams on the cross head, or other moving part of the machinery, so as to strike the former a slight blow, every time the draw 45 roller passes over the said former, so as to insure its being in proper place for catching the next blank.

Extending from the front of the former, to the end of the bed plate, and attached to 50 said bed plate, is the gage plate V, upon which the draw roller runs after passing over the shoe the top of said gage plate being on the same plane with the top of the shoe, so as to give time for the chamfering tool to come up and perform its operation, said gage plate V, holding the draw roller up to the height of the shoe so that in 55 returning it may not drag back the shoe from the former, but pass over it again to 60 smooth down the feathered edges caused by the chamfering tool, and where said gage plate joins the former, it is slightly sloped off so as to chamfer the toes of the shoe from inside to outside.

65 On the extreme end of the bed plate is ar-

ranged, a friction and pressing roller W, supported by its journals in the studs X, and at such height above the bed plate, as to allow the points of the jaws k, which are sloped off for that purpose to pass under, 70 for the purpose of holding down the fork shaped piece T, while chamfering the shoe. By having sets of formers, and fork shaped pieces, and which are readily taken out and put into place, the various sizes of shoes 75 used may be made on one machine.

Attached to one of the ways which guide the cross head, is a crooked lever Y, which is struck by the cross head as it moves back and forth, and gives it a vibratory motion. On a pin on the extreme end of said lever Y, is arranged a hinged arm q, which at the proper intervals forces the blank into proper position for being caught and bent. On the bed plate, or a projection thereof are 80 placed the guides r r, between which the blank is placed, and between which guides the arm q, on the end of the vibrating lever aforesaid, also moves, forcing up the blank 85 into its proper place. On the opposite way, is arranged another and similar lever Z, and which is also operated by the cross head. In the end of said lever Z, is placed a rigid forked arm s, which works in concert with the arm q, and receives the end of the blank 90 upon its inclined jaws, and directs it into proper position for being caught and carried against the former. Both the arms q and s, are by the operation of the machine, 95 after the blank is properly arranged, drawn back so as to allow the said blank to be free. 100

The operation is as follows: The blank being heated and pushed into proper position, is caught by the pins in the ends of the jaws of the fork shaped piece, and forced up against the former where it is caught, the jaws moving on bend the ends of the blank round the former. The drawing roller then strikes the shoe and by means of the pattern by which it is guided, draws the shoe on top to the proper taper, the jaws drawing out the heel part of the shoe against the sides of the gage V, until the rear of the jaw advances, and chamfers the shoe, the roller having passed on to the gage plate in 115 advance of the shoe. As the cross head is drawn back the roller presses down any feathered edge left on the shoe in chamfering, and the pins in the end of the jaws, as they are drawn back with the cross head, 120 catches against the shoe, and carries it back from the former, when it drops through an opening in the bed plate, and between the longitudinal pieces of the frame into a conveyance which carries it to the swaging and punching machine. And as soon as the roller passes back over the former, it (the former) is forced by means of the spring upon which it rests, immediately into position 125 for receiving the next blank.

Having thus fully described my invention what I claim therein as new and desire to secure by Letters Patent is—

In combination with a rotating traveling draw roller, adjustable pattern, and chamfering tool, for forming the shoe, the gage plate for holding up the roller, so as to allow it to return over the shoe thus formed,

and smooth down the feathered edges raised by the chamfering tool as herein described 10 and represented.

ROBERT G. BABCOCK.
